Claims priority, application Great Britain July 22, 1958
2 Claims. (Cl. 198—58)

The invention is concerned with means for feeding textile fibrous materials, e.g. to the scale pan of a weighing machine in which the pan is discharged intermittently, either when the contents attain a predetermined weight or at timed intervals after the desired weight has been fed into the pan, such machine being of the kind comprising a hopper having in its base an endless conveyor which is arranged to feed the material in the hopper towards a spiked lattice by which the material is transported to the point of discharge into the scale pan or other receptacle or apparatus.

With the object of providing a more regular feed of material to the spiked discharge lattice, the present invention proposes automatic feed apparatus comprising an inclined or substantially vertical discharge lattice, a hopper adjacent thereto, an endless lattice forming the base of the hopper, arranged with its upper course moving away from the discharge lattice and its lower course moving towards the same so that material is withdrawn by the upper course from the stock contained in the hopper and carried by the bottom course to the discharge lattice, the discharge lattice being arranged to strip the latter of material fed thereby from the hopper.

Said apparatus may include means within the hopper for operating upon the material conveyed on the upper course of the bottom lattice to maintain a constant rate of removal at any selected lattice speed. The hopper may also contain guard means for holding material stacked therein from contact with that fed to the discharge lattice.

In order that the invention may be more readily understood, reference will be made to the accompanying drawings which illustrate by way of example, a preferred embodiment thereof as applied to the feed apparatus of an automatic weighing and feeding machine.

In the drawings:

FIG. 1 is an elevational section through a machine for delivering fibrous material in even quantities to the pan of a weighing machine, FIG. 2 is a sectional view of the gear change mechanism by which the alternative feed rates are achieved, FIG. 3 is a diagram of the wiring circuit employed with the apparatus, FIG. 4 is the view similar to FIG. 1 showing the opposite side of the machine, FIG. 5 is a fragmentary sectional view on a larger scale, showing the construction of the lattice and other associated parts of the structure of the apparatus, and FIG. 6 is a section taken on the line VI—VI of FIG. 5.

The machine comprises a hopper 1 into which fibrous material may be fed by hand or automatically. In the base of the hopper 1 is arranged an endless lattice 2 shown in dotted lines. The bottom lattice 2 is mounted

2

on three adjustable rollers 2a, 2b and 2c, arranged to be driven in a clock-wise direction so that the upper course of the lattice 2 moves from left to right in the direction of the arrow in a substantially horizontal path. The lattice 2 consists of an endless band carrying transversely disposed slats or lags furnished with upstanding spikes 3 inclined forwardly in the direction of travel to carry the fibrous material towards the rear of the hopper. At the point at which the upper course of the lattice 2 turns about its guiding roller 2b to become the lower course, there is provided a duct 4. Said duct 4 is constituted by sheet metal plates 41, 42 mounted by adjustable brackets 43, bolt mounted, on the wall of the hopper. This duct 4 which is closely spaced to the spikes 3 of the lattice 2, encloses the rollers 2b and the lower course of the lattice 2 in such manner that material extracted from the base of the hopper by the upper course of the lattice 2, is carried through said duct by the spikes on the under course of said lattice.

The lattice 2 is composed of a fabric body 21, bearing cross-bars 22 in which are fixed spikes 3 and incorporating longitudinal leather driving bands 23.

At the point where the upper course of the bottom lattice 2 enters the duct 4, a comb blade 5 arranged to swing to and fro in an arcuate path about its fulcrum 6, removes surplus material from the lattice 2 and pushes this back into the hopper, thus ensuring that an even quantity of material is carried round by the bottom lattice.

The bottom lattice 2 is associated at the forward end of the hopper with an inclined spiked lattice 11, shown in dotted lines. The lattice 11, which is of similar construction to the lattice 2, is arranged to be driven at a faster surface speed than the lattice 2 which has one leg between the rollers 2a and 2c, arranged in a closely spaced substantially parallel path to the lattice 11, so that material is stripped from the bottom lattice.

The material in the hopper 1 is separated from the inclined lattice 11 by a guard 7, thus the quantity of material taken up by the lattice 11 is determined by the amount of material fed along the lower course of the lattice 2 and is independent of the height of the material in the hopper. In this way the amount of material taken up by the lattice 11 is substantially constant at any selected lattice speed.

Although in the preferred embodiment the guard 7 only prevents material from contacting the lattice 11, it may, if desired, be extended to cover a portion of the bottom lattice 2; moreover, the length of the bottom lattice 2 which can be covered by the said extension of the guard 7, may be varied to alter the "bite" of the lattice 2 on the material in the hopper. The adjustability of the guard 7 is readily accomplished by the provision of adjustable brackets 70 (designated in FIG. 5 and shown in the dotted lines in FIG. 1), bolt mounted on the wall of the hopper while the varying of the length of the bottom lattice 2 results from the provision of adjustable brackets 200 (designated in FIG. 5 and shown also in FIG. 1) which mount the rollers 2a, 2b and 2c.

The material taken up by the lattice 11 is presented to a second comb 9 and to a rotary stripping brush 12, by

which it is removed from the lattice spikes and fed as a substantially continuous stream past a trap door 13 into a scale pan 14, which latter is arranged to be periodically opened by the operation of a rotary cam 141 in well known fashion. The shaft carrying the cam 141 also carries two cycle-control wheels of which one is shown at 142. Said wheels carry contact-members 143 which are arranged to actuate two switches SW/3 and SW/4 respectively. The scale pan 14 is balanced by a weighted arm 19 which is pivoted on a knife edge 191 and carries the scale pan 14 at one end and a balance weight 192 at the other end, the arrangement being such that when the scale pan 14 is emptied, the arm 19 is moved downwardly about its fulcrum 191 to close the switch SW/2, and when the scale pan 14 has been filled to a predetermined extent, the arm 19 rises, opening the switch SW/2 and closing the switch SW/1.

The main shaft 16 is driven from the input shaft 15 through gearing enclosed in the casing 161. The comb 5 receives its pivoted motion about the fulcrum 6 through the medium of an eccentric 163 (FIG. 1) mounted on said shaft 16 and a rod 164. The shaft 16 also drives the comb 9 through the medium of an eccentric 165 (FIG. 4), the comb being caused to oscillate about its fulcrum 91 by the eccentric rod 166. Said input shaft 15 is belt-driven from the driving-shaft of the carding machine. The feed brush 12 receives a constant speed drive from said shaft 15 through a chain 121, a counter-shaft 122 and a belt 123. The spiked lattice 11 is driven by the shaft 16 through the medium of a sprocket 36, a chain 31, a sprocket 32 and gears 33, 34, 35, 36 and 37, the gear 37 being fixed on the lattice driving shaft 38. The arrangement is such that said shaft 16, as is shown in FIG. 2, is driven from the input shaft 15 by either of two alternative gear-trains respectively giving a normal rate of delivery by the lattice 11 or a diminished rate as the weighing operation is almost concluded. The shaft 15 carries two spur gears, 151 and 152, which are respectively in mesh with pinions 171, 172 which are loose on an intermediate shaft 17. An electro-magnetic double clutch 18, comprising electromagnetic windings 181 and 182 which are respectively attached to the gears 171, 172 and a clutch member 183 supplying to the shaft 117 and capable of sliding movement to engage whichever of the windings 181, 182 is energized, the effect being to select one or other of said gears 171, 172 to be clutched to the shaft 17, which is connected to the lattice drive shaft 16 by gears 173, 162. That is to say, if the clutch is set to select the gear 171, the lattice 11 will be run at normal feed rate; if the gear 172 is selected, the lattice 11 will run at "trickle" rate. The gear wheels 162, 173 are change wheels and can be substituted by others giving a different ratio when it is desired to alter the speeds of the lattice 11 to suit particular production rates or blends of material. A gear 39 on the bottom shaft 111 of the lattice 11 drives a gear 40 on the roller 26 of the lattice 2, so that alteration of the speed of lattice 11 will give a corresponding alteration to the speed of the lattice 2.

The operation of filling a scale pan takes place in two stages, during the first of which a predetermined amount of material is fed by the lattice 11 and brush 12 at a high speed. Starting with an empty scale pan 14 and all switches in the positions shown in FIG. 3, starter switch SF is closed to supply current to the primary of a transformer T/1 via switch SW/1 which is in the normal closed position. Relay RL/1 is energized as it is connected to the secondary winding of the transformer T/1. The contact of RL/1 moves to the NO position, and a high speed clutch winding 181 is energized through the potentiometer RV/1, thus driving the lattice 11 at high speed to deliver materials to the weigh pan 14.

When the weight of the materials fed into the scale pan 14 has reached a predetermined value, the arm 19 is tripped, releasing, that is opening, switch SW/2 and there-

by deenergizing relay RL/1, the contacts of which revert to the NC position. The high speed clutch winding 181 is thus deenergized and the low speed clutch winding 182 is energized via potentiometer RV/2. The lattice 11 is now driven at a slow speed, and material enters the pan 14 at a trickle rate. When the weight of material in the pan 14 has reached a desired total value, the arm 19 operates the switch SW/1 moving it from NC to NO position, deenergizing the clutch winding 182 by breaking the circuit to the transformer T/1 and energizing the solenoid SOL, the function of which is to close the trap doors 13 to prevent further feed of material into scale pan 14. This condition persists until the scale pan is open to discharge its contents when the arm 19 releases the switch SW/1 and again close the switch SW/2 to recommence the cycle.

During the cycle the switch SW/4 is momentarily depressed by the cycle wheel 142 but without effect since the switch SW/1 is then in the NO position.

If however, the scale pan has not received its full contents when the switch SW/4 is closed by the cycle wheel, in which case the switch SW/1 will be in the NC position, the relay RL/2 will be energised, and indicator lamps L, L will be illuminated via the contact RL/2/2. When the switch SW/1 changes over to the NO position, the relay RL/2 remains energised via the switch SW/3, and the relay contact RL/2/1, so that the lamps L, L will remain lit. The relay RL/2 is re-set at each cycle when the switch SW/3 is momentarily depressed by the appropriate cycle wheel 142 just before the actuation of the switch SW/4. Thus the arrangement gives a virtually continuous indication that the scale pan has not yet received its full charge, until the complete charge is received, when the switch SW/4 is closed.

The rotary brush 12 is preferably so located in relation to the lattice 11 that when the brush first contacts the spikes of the lattice, the spikes are in radial alignment with the bristles or the like so that the fibrous material carried by the brush is stripped therefrom. Since the linear speed of the bristles exceeds that of the lattice spikes, they operate to strip fibres from said spikes as successive rows thereof are declined away from the brush.

Although the preferred embodiment of the invention has been described with reference to an automatic weighing and feeding machine, the automatic feed apparatus, may be used in any machine where fibrous material fed into a hopper, is required to be delivered therefrom in even quantities by a discharge lattice.

What I claim as my invention and desire to secure by Letters Patent is:

1. Automatic feed apparatus for textile fibrous materials comprising a substantially upright discharge lattice, means for driving said discharge lattice, a hopper adjacent said discharge lattice for receiving textile fibrous materials, an endless bottom lattice forming the base for the hopper and incorporating an upper substantially horizontal course extending away from said discharge lattice, a lower course extending downwardly and toward said discharge lattice and a substantially upright course extending in a path parallel to and adjacent the lower portion of said substantially upright discharge lattice, means for driving said bottom lattice with its upper course moving away from the discharge lattice, its lower course moving towards the discharge lattice and its substantially upright course moving in the same direction as said discharge lattice, said means for driving said discharge lattice and said means for driving said bottom lattice being arranged for driving said discharge lattice at a greater surface speed than said bottom lattice, the discharge lattice being positioned relative to the bottom lattice for stripping the bottom lattice of the material carried along the upright course thereof, guard means for holding material stacked in said hopper from contact with the material which is fed to the discharge lattice, and a duct enclosing the

bottom lattice at the point of reversal of the upper course and along its lower course to the discharge lattice, said duct being spaced a limited distance from the surface of the bottom lattice to control the quantity of material fed to the discharge lattice.

2. Apparatus as claimed in claim 1, wherein means are provided for operating upon the material withdrawn along the upper course of the bottom lattice to maintain a regular feed of material and said means comprises a comb pivotally mounted in pendulum fashion adjacent the end 10 of the upper course of the bottom lattice and is positioned to swing across the lattice to remove excess material thereon.
